(57) **CLAIM**

The ornamental design for a chemical heating volatilizing apparatus, as shown and described.

DESCRIPTION

FIG. 1 is a front, top, right side perspective view of a chemical heating volatilizing apparatus, showing my new design;

FIG. 2 is a front elevational view thereof;

FIG. 3 is a right side view thereof, the left side view being a mirror image;

FIG. 4 is a top plan view thereof;

FIG. 5 is a rear elevational view thereof; and,

FIG. 6 is a bottom plan view thereof.

The broken lines are for illustrative purposes only and form no part of the claimed design.
